Primary Examiner — Cynthia Ramirez*Assistant Examiner* — Michael A Maharajh*(74) Attorney, Agent, or Firm* — Fross Zelnick Lehrman & Sissu, P.C.; Charles T. J. Weigell, Esq.(57) **CLAIM**

The ornamental design for an exercise apparatus, as shown and described.

DESCRIPTION

FIG. 1 is a perspective view of an exercise apparatus showing our new design, shown in an open position; FIG. 2 is a front view thereof; FIG. 3 is a back view thereof; FIG. 4 is a left side view thereof; FIG. 5 is a right side view thereof; FIG. 6 is a top view thereof; FIG. 7 is a bottom view thereof; and, FIG. 8 is a perspective view thereof, shown in a closed position.

The broken lines shown in the figures are for the purpose of illustrating portions of the exercise apparatus, which form no part of the claimed design.
